UNITED STATES PATENT OFFICE.

MARCUS L. KELLY, OF GARFIELD, ARKANSAS.

FELLY.

1,271,038.

Specification of Letters Patent.

Patented July 2, 1918.

Application filed November 12, 1917. Serial No. 201,554.

To all whom it may concern:

Be it known that I, MARCUS L. KELLY, a citizen of the United States, residing at Garfield, in the county of Benton and State of 5 Arkansas, have invented certain new and useful Improvements in Fellies, of which the following is a specification, reference being had to the accompanying drawings.

This invention relates to certain improvements in armor for wheel fellies and it is an 10 object of the invention to provide a novel and improved device of this general character which is adapted to overlie a side surface of the felly to protect the felly proper against 15 injury as by contact with rocks or other obstructions and also serves to prevent the felly from becoming saturated which otherwise results in a shrinkage of the felly after drying again and a loosening of the metallic 20 tire thereon.

The invention consists in the details of construction and in the combination and arrangement of the several parts of my improved felly wherein certain important advantages are attained and the device rendered simpler, less expensive and otherwise 25 more convenient and advantageous for use, as will be hereinafter more fully set forth.

The novel features of my invention will 30 hereinafter be definitely claimed.

In order that my invention may be the better understood I will now proceed to describe the same with reference to the accompanying drawings wherein:

35 Figure 1 is a fragmentary view in elevation illustrating an armor constructed in accordance with an embodiment of my invention and in applied position; and

Fig. 2 is an enlarged sectional view taken 40 substantially on the line 2—2 of Fig. 1.

As disclosed in the accompanying drawings F denotes a wooden felly as generally employed in the production of wheels and T denotes a metallic tire disposed circumferentially therearound. In order to protect the felly F against the action of water it is customary to provide the same with a coating of paint. However, in order to further protect the side faces of the felly I find it of particular advantage to arrange adjacent the opposite faces of the felly F the metallic plates 1 herein disclosed as arcuate

in form and having their marginal portions provided with the inwardly directed flanges 2 adapted to overlie the outer and inner face 55 of the felly. Disposed through the felly and the plates 1 are the rivets 3 whereby said plates are effectively maintained in applied position. As herein embodied the adjacent ends of the plates 1 are in overlying relation 60 although if preferred a single annular plate may be employed at each side of the felly. This plate in addition to affording means to further prevent moisture from penetrating the felly F serves to prevent the paint applied directly to the felly from being knocked off by contact with rocks or other obstructions.

After the plates 1 have been applied it is preferred that a coating of paint be also applied to the exposed faces thereof together with striping if preferred. In applying the plates 1 it is also to be noted that the outer marginal flanges 2 are interposed between the tire T and the peripheral face of the 75 felly F.

From the foregoing description, it is thought to be obvious that a felly constructed in accordance with my invention is particularly well adapted for use by reason of the 80 convenience and facility with which it may be assembled and operated and it will also be obvious that my invention is susceptible of some change and modification without materially departing from the principles and 85 spirit thereof and for this reason I do not wish to be understood as limiting myself to the precise arrangement and formation of the several parts herein shown in carrying out my invention in practice except as hereinafter claimed.

I claim:

1. In combination with the felly of a wheel, metallic plates secured to the felly and overlying the side faces thereof, marginal portions of the plates being provided with inwardly directed flanges overlying the inner and outer faces of the felly, the plates at each side of the felly being arcuate, the end portions of adjacent plates overlying.

2. In combination with the felly of a wheel, plates overlying the side faces of the felly and having marginal portions provided with flanges overlying the outer and

inner faces of the felly, and members disposed through the felly and the plates for holding said plates in applied position.

3. In combination with the felly of a wheel, and a tire mounted thereon, plates overlying the side faces of the felly, and means for securing the plates to the felly, said plates being provided with marginal flanges overlying the outer and inner faces

of the felly, the flanges overlying the outer face of the felly being positioned intermediate the outer face of the felly and the tire.

In testimony whereof I hereunto affix my signature in the presence of two witnesses.

MARCUS L. KELLY.

Witnesses:

W. T. PATTERSON,
H. J. PATTERSON.
